UNITED STATES PATENT OFFICE.

HERVE D. WILKINS, OF ROCHESTER, NEW YORK.

SWELL FOR PIPE-ORGANS.

SPECIFICATION forming part of Letters Patent No. 361,562, dated April 19, 1887.

Application filed March 9, 1886. Serial No. 194,622. (No model.)

To all whom it may concern:

Be it known that I, HERVE D. WILKINS, a citizen of the United States, residing at Rochester, in the county of Monroe and State of New York, have invented a new and useful Improvement in Swells for Pipe-Organs, of which the following is a specification, reference being had to the accompanying drawings.

10 My invention relates to swell-boxes for pipe-organs having either single or double swell-folds; and it consists of the novel arrangement and operation of the folds, as hereinafter described.

15 The object of my invention is to produce a steady progressive crescendo from the greatest possible piano to the greatest possible forte, and to furnish means by which the organist shall have perfect control of the swell-folds at all points of their movement.

20 In the accompanying drawings, Figure 1 is a front elevation of a double-fold swell-box having my approved apparatus attached to it. Fig. 2 is a horizontal section of the same; and Fig. 3 is a detail drawing of a portion of the folds, showing the construction.

25 A is the swell-box, containing all the pipes known as the "swell-organ," and from which a crescendo is obtained by the opening and closing of the folds or shutters C. A box, B, is built into the front of the swell-box, open on its front, and the opening provided with and entirely filled by the two sets of folds C C. The folds of each set are connected together by rods H H, pivoted to the elbows I I on each fold in the usual manner, so that all move together.

30 The folds C C have pivots *aa* on their ends, which pivots fit into sockets in the frame of the box B, and the folds turn freely on such pivots. The folds are rabbeted on their edges, as shown at *d*, Figs. 1 and 3, in order to more effectually shut in the sound of the swell-organ pipes when closed. A rod, D, passes through the box B, midway between the two sets of folds, and having bearings in the edges thereof, through which it reciprocates, and is connected in the usual manner with the swell-pedal located below the key-board of the organ, by which pedal the organist opens and closes the swell-folds. The rod D is provided

35 with elbows E E, or other suitable connections secured to it, to which are pivoted the rods F F, and the two end folds, or any pair of them opposite each other, are provided with elbows G G, to which the rods F F are also pivoted. These lugs E E and G G are so placed that when the folds C C are closed the rods F F are at right angles with the folds and rod D. The organist, to open the folds, operates the swell-pedal, which causes the rod D to travel longitudinally, carrying with it the rods F F and opening the folds, as shown in Fig. 3. From this arrangement of the mechanism it will be observed that when closed it will take more travel of the rod D to open the folds a given distance than when the same are nearly wide open, and near the position shown in dotted lines in Fig. 3. This is of great practical utility, for the successful operation of a swell 70 depends upon the ability of the organist to effect a gradual opening of the swell-folds, particularly at the beginning of a crescendo, for the change from piano is most marked at the moment the folds begin to open, and less 75 and less marked as they progress to the wide-open position.

75 It has hitherto been difficult to produce a fine gradation of sound when the folds are just opening or closing, because the devices heretofore used of which I am aware have given the organist least control of the movement of the folds when nearly closed. My device, by requiring more motion of the pedal to move the folds a given distance when near 80 the closing-point than when partly open, gives the organist perfect control of the swell at the moment when such control is most needed in order to produce the fine gradation of the crescendo.

85 Another feature of my invention is that the device, as already described, applies the force necessary to open or close the folds in a line substantially at right angles to them at all points of the movement and in the direction most efficient for their easy operation.

90 Another feature of my invention is the opening of the two sets of folds in opposite directions, as shown in Fig. 3. Hitherto when double folds have been used they have been opened simultaneously, but in the same direction, and it has been demonstrated in prac-

tice that it is not practicable to open them but half-way—that is, at an angle of forty-five degrees with the swell-box—because if a greater opening be attempted the outer set of 5 folds turn out of line with the inner set and intercept in a measure the sound issuing from the swell-box through the inner folds, and produce a check in the crescendo and a momentary weakening of the sound. By opening the folds in opposite directions, as shown in Fig. 3, this difficulty is overcome, and the folds may be opened to their fullest extent, for they do not come into line until fully opened and at right angles to the swell-box, without 15 any check to the crescendo and without the outer folds obstructing or weakening the sound. This method of operating double folds secures both the subdued effect of the double folds when closed and the forte of the single folds 20 when wide open, and admits of a greater distance between the extremes of piano and forte than has hitherto been possible in a swell for pipe-organs.

My invention is applicable to single or 25 double and to vertical or horizontal folds; but more satisfactory results are obtained by the use of double folds, as shown in the drawings. When applied to single folds, it should be placed outside of the same. The device 30 may be connected to the ends of the folds, at

the top or bottom, or at any intermediate point, as may be found most convenient in each particular case.

What I claim is—

1. The combination, with a pipe-organ swell- 35 box and swell-pedal, of the rod D, lugs E E and G G, rods F F, and folds C C, substantially as and for the purposes set forth.

2. A pipe-organ having a swell-box, provided with two sets of folds, one directly in 40 front of the other, said folds being arranged substantially as described, so as to be moved simultaneously in opposite directions by a single pedal, with which they are connected by a series of levers, as set forth.

3. In a pipe-organ, the combination, with the swell-pedal, of the folds C, lugs G and E, and rods D and F, arranged as described, so that a uniform and even motion of the pedal causes the folds to open with a constantly-increasing motion until wide open, and to close with a constantly-decreasing motion until entirely closed, whereby a steady progressive crescendo and a steady retrogressive diminuendo are obtained, substantially as hereinbefore set forth.

HERVE D. WILKINS.
